UNITED STATES PATENT OFFICE.

WILLIAM J. DEVINE, OF NORWALK, CONNECTICUT.

INSULATOR.

No. 869,163.

Specification of Letters Patent.

Patented Oct. 22, 1907.

Application filed July 23, 1907. Serial No. 385,147.

To all whom it may concern:

Be it known that I, WILLIAM J. DEVINE, a citizen of the United States, residing at Norwalk, in the county of Fairfield and State of Connecticut, have invented 5 new and useful Improvements in Insulators, of which the following is a specification.

This invention relates to insulators and more especially to blocks with coöperative parts which may be built upon each other so as to carry a number of electric wires at certain points and locations which have been heretofore difficult to arrange and carry them as will be more fully described in the following specification, set forth in the claims and illustrated in the accompanying drawings where like reference letters are 10 used in the various views to designate the same parts.

Figure 1 is a perspective view of several of the blocks located on the corner of a beam and carrying the wires of a circuit. Fig. 2 is a cross sectional view of several superimposed blocks through the notches which contain the wires. Fig. 3 is a vertical longitudinal sectional view of a block. Figs. 4 and 5 are views of a modified form of insulating block. Fig. 6 is a view showing how the insulators carry a wire along the ceiling and the beams of a building.

25 A very serious obstacle heretofore in the stringing of electric wires has been the turning of angles and corners and the great source of danger in electric wiring for high voltage is where the wire comes in contact with the corners of posts or beams, the covering is worn off by chafing and short circuiting through the woodwork follows and fire often results. In order to overcome these and other objections to the common form of block, which are designed and constructed for use on flat surfaces only, the present invention consists of 30 a block of porcelain, rubber, glass or other insulating material of any desired length according to the number of wires to be strung and having along its under side a groove 10 with two flat sides separated at an angle of preferably ninety degrees. This groove 10 is formed 35 in the block for the purpose of locating it on the corner of posts, joists or other timbers of a building where the wiring is to be strung and the block used. Transverse to the groove 10 are grooves 11 which carry the wires, and the upper face of the block is provided with a rib 40 45 12 whose sides correspond with those of the groove 10 into which it is adapted to fit and this rib also has transverse grooves 13 coinciding with the grooves 11 and in these grooves the wires are contained and clamped.

Screw holes 14 are formed vertically in the block through which screws or spikes are passed to aline the 50 blocks, secure them to the timber and at the same time clamp the wires in the grooves 11 and 13.

In practice, a series of two or more blocks is adapted to be used. The groove of one block of the series is adapted to receive the rib of the next adjacent block, 55 thereby providing an interlocking connection between the blocks. The groove of one of the end blocks of the series is adapted to receive the corner of a timber or other support to which the series is secured.

Where it is desired to use these blocks on plane surfaces, the feet formed at each side of the groove serve as a ready support and the blocks may be built up and secured by means of screws or spikes.

These insulators are thus serviceable in stringing wires in all directions and readily overcome the question of turning corners.

In Figs. 4 and 5 the modified form of the block there shown is one of the round type with a groove 15 in its lower side for the purpose of securing it to the corner of a post or beam and having wire holding grooves 16 in 70 its upper face, a cap 17 with corresponding grooves 17' is provided to be secured on the block by the screw or spike 18 which not only secures it to the woodwork but grips the wire.

It is obvious that other modified forms may be adopted with means for securing same to the corners or the plane face of woodwork without departing from the essential features above described.

What I claim as new and desire to secure by Letters Patent is:

1. In insulating blocks, the combination with blocks of electric non-conductive material, of interlocking means for adjacent blocks, means for fitting same to the corners of woodwork or other material and means for securing the blocks together and to the corner of the woodwork.

2. In insulating blocks having grooves along their lower sides to fit angular structures and transverse grooves or notches for the wires, the combination of ribs on the upper sides of the blocks adapted to fit the grooves and having corresponding transverse notches, and means for holding the blocks together to clamp the wires.

In testimony whereof, I affix my signature in presence of two witnesses.

WILLIAM J. DEVINE.
